CLAIM

The ornamental design for a collapsible child toilet seat, as shown and described.

DESCRIPTION

FIG. 1 is a top perspective view of a collapsible child toilet seat showing our new design;

FIG. 2 is a top view thereof;

FIG. 3 is a bottom view thereof;

FIG. 4 is a right side view thereof;

FIG. 5 is a front view thereof;

FIG. 6 is a left view thereof; and,

FIG. 7 is a rear side view thereof.

The broken lines illustrate portions of the collapsible child toilet seat that form no part of the claimed design.
